(57)

CLAIM

The ornamental design for a switch equipment for electrical power control as shown and described.

DESCRIPTION

1. Switch, equipment for electrical power control

1.1 : Perspective

1.2 : Front

1.3 : Back

1.4 : Right

1.5 : Left

1.6 : Top

1.7 : Bottom

The broken lines in the drawing are for the purpose of illustrating portions of the article that form no part of the claimed design.

1 Claim, 7 Drawing Sheets
